UNITED STATES PATENT OFFICE.

DANIEL B. JACOBS, OF NEW YORK, N. Y.

DOUBLETREE-CLIP.

1,126,477.

Specification of Letters Patent.

Patented Jan. 26, 1915.

Application filed March 6, 1914. Serial No. 822,915.

To all whom it may concern:

Be it known that I, DANIEL B. JACOBS, a citizen of the United States, and a resident of the city of New York, borough of Manhattan, in the county and State of New York, have invented a new and Improved Doubletree-Clip, of which the following is a full, clear, and exact description.

The object of the invention is to provide a new and improved doubletree clip arranged to allow convenient attachment of the clip to doubletrees of various thicknesses and width, to permit of adjusting the clip in case of shrinkage of the wood of the doubletree, to securely hold the clip in position, and to allow use of the clip at the middle of the doubletree for connection with the draw pin and hammer strap as well as on the ends of the doubletree for connection with the swingletree.

In order to accomplish the desired result use is made of top and bottom plates extending from the top and bottom of the doubletree and projecting beyond the sides thereof, fastening means connecting the ends of the said plates with each other at one side of the doubletree and connecting and retaining means between the other ends of the plates at the other side of the doubletree. Use is also made of a bolt connecting the ends of the plates with each other, and a spool held on the said bolt for engagement by the connecting link or ring of a swingletree to support the latter from the clip at the end of the doubletree.

A practical embodiment of the invention is represented in the accompanying drawings forming a part of this specification, in which similar characters of reference indicate corresponding parts in all the views.

Figure 1 is a plan view of the clip as applied to a doubletree mounted on the pole of a vehicle; Fig. 2 is an enlarged plan view of one of the clips as applied to the end of the doubletree; Fig. 3 is a cross section of the same on the line 3-3 of Fig. 4; Fig. 4 is a sectional side elevation of the same on the line 4-4 of Fig. 2; Fig. 5 is a sectional side elevation of a modified form of the attaching means of the clip; Fig. 6 is a similar view of another modified form of the attaching means; Fig. 7 is a like view of another modified form of the attaching means; Fig. 8 is a perspective view of a modified form of the clip; Fig. 9 is a sectional side elevation of the same; Fig. 10 is

a plan view of the blank for forming the top plate of the clip shown in Figs. 8 and 9; Fig. 11 is a similar view of the blank for forming the bottom plate of the clip shown in Figs. 8 and 9; Fig. 12 is a plan view of another modified form of the clip; and Fig. 13 is a side elevation of the same.

As shown in Fig. 1, the doubletree A is held on the top of the vehicle pole B and provided with the usual hammer strap C and draw pin D adapted to engage a clip E held on the middle of the doubletree A, similar clips E' being arranged at the ends of the doubletree for connection with the links or rings F for supporting the swingletrees from the said clips E', as hereinafter more fully explained.

Each of the clips E and E' is formed of a top plate G and a bottom plate H, the plates extending across the top and bottom of the doubletree A, the said plates G and H being provided with extensions G', G² and H', H² extending beyond the opposite sides of the doubletree A. The extensions G', H' are provided with integral flanges G³, H³ extending toward each other and fitting against the corresponding side of the doubletree A, and the said extensions G' and H' are provided with lugs G⁴ and H⁴ extending toward each other and merging with the flanges G³ and H³. Bolts I pass loosely through the extension G' and the lugs G⁴ and screw into the lugs H⁴ thus connecting the plates G and H with each other at one side of the doubletree A. Washers or aliners J are interposed between the lugs G⁴, H⁴ and the flanges G³, H³, and in case the doubletree A shrinks the said washers can be removed to allow of drawing the plates G and H tight again on the top and bottom of the doubletree A by correspondingly screwing up the bolts I. The extensions G' and H' are provided intermediate the bolts I with registering apertures H⁵ for the passage of the draw pin D to hold the doubletree A in place on the pole B and hammer strap C, as plainly indicated in Fig. 1. One or both of the apertures G⁵, H⁵ may be used for the reception of stay chains connected with the clips E' at the ends of the doubletree A, it being understood that the clips E' are reversely used on the doubletree A relative to the clip E, as shown in Fig. 1.

The projections G², H² at the other ends of the plates G and H are connected with each

other at the other side of the doubletree A by a bolt K extending loosely through the extension G² and screwing into the extension H², as plainly shown in Figs. 4, 5, 6 and 7. On this bolt K is held a spool L and washers N are mounted on the bolt intermediate the upper and lower ends of the spool and the corresponding extensions G², H² so that in case the doubletree A shrinks 10 and the plates G and H are adjusted then one or several of the washers N may be removed to compensate for the shrinkage in the thickness of the doubletree A. The spool L is engaged by the link or ring F of the swingletree to be supported from the end clips E'. The under surface of the top plate G is provided with an integral rib G⁶ and a similar rib H⁶ is formed on the top of the bottom plate H, and the said ribs G⁶, H⁶ 20 extend in staggered relation across the doubletree A and engage grooves therein so as to securely hold the top and bottom plates G and H from lateral displacement on the doubletree A. The middle clip E may be 25 provided with a spool L and washers N on the bolt K, but preferably a hook O is employed having a hub O' fitting onto the bolt K intermediate the extensions G², H², as shown in Fig. 7. By this arrangement the 30 doubletree A may be conveniently hooked onto the ring on the clevis of a plow or the like, whenever it is desired to use the doubletree for such a purpose, instead of on a vehicle, as shown in Fig. 1. In a like manner a clevis P may be directly engaged with the bolt K instead of the spool L or the hook O, as shown in Fig. 6. As indicated in Fig. 5, the bottom plate H has its extension H² diverging into a return bent hook 35 H⁷ to confine the ring F in the hook H⁷ and thus prevent the swingletree from becoming accidentally detached from the corresponding clip E' of the doubletree A.

In the modified form shown in Figs. 8, 9, 45 10 and 11, the clip is formed of a top plate Q and a bottom plate R, both preferably formed of flat blanks, as indicated in Figs. 10 and 11. The plate Q is provided with angular arms Q', Q² and similar arms R', R² 50 are formed on the bottom plate R, the said arms extending toward each other and fitting opposite sides of the doubletree on which the clip is to be used. The arm Q' is provided with an outwardly-extending horizontal flange Q³ and the arm R' terminates in an outwardly-extending doubled-up flange R³ also forming an eye R⁴. The flanges Q³ and R³ are connected with each 55 other by a bolt S which extends through the flange R³ to permit of drawing the plates Q and R tightly in position on the top and bottom of the doubletree. The arm Q² terminates in a flange Q⁴ and the arm R² terminates in a doubled-up flange R⁵, and the flanges Q⁴ and R⁵ are connected with 60

each other by a bolt T which extends loosely through the flange Q⁴ and screws in the doubled-up flange R⁵. A spool U is held on the bolt T for engagement by the link or ring F to support the swingletree from the corresponding clip on the doubletree. The plates Q and R are provided with struck-up ribs Q⁵, R⁶ adapted to engage corresponding recesses in the top and bottom of the doubletree to hold the clip against lateral movement. 75

In the modified form shown in Figs. 12 and 13, the top and bottom plates V and W are provided at one end with a filling piece X secured in place by bolts Y extending through the top plate V and screwing in the bottom plate W. The filling piece X is adapted to abut against one side of the doubletree, and its outer face is provided with an eye X' for engagement by a draw pin to hold the doubletree in position on the pole. The top plate V and the bottom plate W are provided at the ends opposite the filling piece X with angular arms V', W' terminating in flanges V², W² connected 90 with each other by a bolt T', on which is mounted to rotate loosely a spool U' similar to the spool U above mentioned. The bolt T' extends loosely through the flange V² and screws in the flange W². The top plate V and the bottom plate W are provided with ribs V³ and W³ adapted to engage the top and bottom of the doubletree to hold the clip against lateral movement on the doubletree. 95

It is understood that the clip shown in Figs. 8 and 9 as well as the clip shown in Figs. 12 and 13 can be used either on the middle of the doubletree A or at either end thereof, the same as the clips E and E' 105 above described and shown in Fig. 1.

Having thus described my invention, I claim as new and desire to secure by Letters Patent:

1. A doubletree clip, comprising top and bottom plates extending across the top and bottom of the doubletree and projecting beyond the sides thereof, the under face of the said top plate having a longitudinally-extending rib and the upper face of the bottom plate having a similar rib, the ribs being embedded in the top and bottom of the doubletree, fastening means connecting the ends of the said plates with each other at one side of the doubletree, and connecting and retaining means between the other ends of the plates at the other side of the doubletree. 110

2. A doubletree clip, comprising top and bottom plates extending across the top and bottom of the doubletree and projecting beyond the sides thereof, the under face of the said top plate and the upper face of the said bottom plate being provided with longitudinally-extending ribs staggered in a trans- 125

verse direction and embedded in the top and bottom of the doubletree, fastening means connecting the ends of the said plates with each other at the one side of the doubletree, 5 and connecting and retaining means between the other ends of the plates at the other side of the doubletree.

3. A doubletree clip, comprising top and bottom plates extending across the top and 10 bottom of the doubletree and projecting beyond the sides thereof, the said top and bottom plates having ribs embedded in the top and bottom of the doubletree to hold the clip against transverse movement, the ends 15 of the said top and bottom plates at one side of the doubletree having integral flanges fitting against the said side of the doubletree to hold the clip against forward movement 20 on the doubletree, connecting means adjacent the said flanges and engaging the projecting ends of the said top and bottom plates to connect the said plates with each other at the side of the doubletree on which the flanges are located, and connecting the 25 retaining means connecting the other ends of the top and bottom plates with each other at the other side of the doubletree.

4. A doubletree clip, comprising top and bottom plates extending respectively across 30 the top and bottom of the doubletree, both ends of each plate extending beyond the sides of the doubletree, the ends of the said plates being provided with sets of integral lugs, the lugs in each set extending toward 35 each other at one side of the doubletree, washers between the lugs of each set, bolts passing through the end of the top plate

and the lugs thereon, the bolts also passing through the said washers and screwing into the lugs of the bottom plate, the said sets of 40 lugs being spaced apart and the ends of the top and bottom plates between the said sets of lugs being apertured, and connecting and retaining means connecting the other ends of the plates with each other at the other 45 side of the doubletree.

5. A doubletree clip, comprising top and bottom plates extending respectively across the top and bottom of the doubletree, both 50 ends of each plate extending beyond the sides of the doubletree, the ends of the said plates being provided with sets of integral lugs, the lugs in each set extending toward each other at one side of the doubletree, washers between the lugs of each set, bolts 55 passing through the end of the top plate and the lugs thereon, the bolts also passing through the said washers and screwing into the lugs of the bottom plate, the said sets of lugs being spaced apart and the ends of 60 the top and bottom plates between the said sets of lugs being apertured, a vertically-disposed bolt connecting the other ends of the top and bottom plates with each other, and a spool held on the said bolt, the spool 65 having a hook.

In testimony whereof I have signed my name to this specification in the presence of two subscribing witnesses.

DANIEL B. JACOBS.
